Application April 29, 1942, Serial No. 440,931

3 Claims. (Cl. 260—683.4)

1

The present invention relates to improvements in the alkylation of isoparaffinic hydrocarbons with olefinic hydrocarbons to form hydrocarbons boiling within the range of gasoline and particularly suitable for use as a high antiknock aviation grade motor fuel.

In the alkylation of an isoparaffin with an olefin in the presence of a suitable alkylation catalyst to form high antiknock predominantly isoparaffinic gasoline hydrocarbons, a considerable problem is generally presented in the elimination of hydrocarbons lower boiling than the isoparaffinic reactant from the alkylation system, particularly in the separation of the hydrocarbon mixture discharged from the alkylation zone for the recovery of the desired alkylate. This problem primarily involves fractionation difficulties in the handling of relatively large amounts of reactants and unreactive materials utilized in the formation of a relatively small amount of desired alkylate with the consequent large equipment required to accomplish the necessary fractionation.

Since it is necessary to have the isoparaffinic reactant, e. g., isobutane, present in an amount in substantial excess of that required to react with the olefinic reactant, e. g., a butene, in the alkylation zone in order to obtain a substantial degree of alkylation, it becomes desirable from an economic viewpoint to recycle the excess isoparaffinic reactant separated from the alkylate to the alkylation zone to maintain the desired ratio of isoparaffin to olefin therein. At the same time, however, the recycling of hydrocarbons lower boiling than the isoparaffinic reactant, e. g., propane, which is invariably introduced into the alkylation system along with the C₄ fraction containing the isobutane and/or the butene, is to be avoided as much as possible since, for optimum operation, it is necessary to maintain a low concentration of propane in the alkylation zone.

Accordingly, it is an object of my invention to provide an improved method of fractionating the hydrocarbon mixture discharged from the alkylation zone in an isoparaffin-olefin alkylation system whereby a material saving in equipment and operating costs can be effected.

It is a further object of my invention to provide an improved method of separating the isobutane and the propane from the hydrocarbon effluent from the alkylation zone in an isobutane-butene alkylation system for recycling of the isobutane to the alkylation zone and elimination of the propane from the alkylation system.

It is another object of my invention to provide

2

a convenient method of eliminating undesirable propane from an isobutane-butene alkylation system without the use of excessive fractionating equipment and with only a negligible loss of valuable isobutane.

Further objects and advantages of my invention will be apparent from the following description of a preferred form of embodiment thereof taken in connection with the accompanying drawing, which represents a typical flow sheet of a process embodying my invention.

For convenience only, my invention will be described in connection with the alkylation of isobutane with a butene in the presence of concentrated sulfuric acid to form high antiknock gasoline containing a major proportion of iso-octanes. It will be appreciated, however, that my invention is not so restricted but is applicable to the alkylation of any isoparaffin with any olefin, whether such materials are normally gaseous or not, in the presence of any suitable alkylation catalyst to form predominantly isoparaffinic hydrocarbons suitable for use as a high antiknock motor fuel.

25 According to my invention, isobutane and butene in the desired proportions, containing propane unavoidably admixed therewith, are alkylated in the presence of concentrated sulfuric acid to form high antiknock hydrocarbons boiling within the range of gasoline. During the alkylation reaction the isobutane is maintained in excess of that required to react with the butene. The resulting alkylate product is separated from the acid and is neutralized, and the excess isobutane and lower boiling hydrocarbons including propane are separated as overhead from the alkylate in a prefractionating step. The isobutane overhead contains the propane in a higher concentration than at any other point in the alkylation system, and the propane is concentrated in a stream of relatively small volume at a point in the alkylation system where it can be most readily eliminated therefrom by customary fractionating operations. This overhead stream is subjected to a further fractionation step to separate the propane from the isobutane. The propane is eliminated from the system, and the isobutane is recycled to the alkylation zone.

In accordance with my invention, a C₄ fraction of normally gaseous hydrocarbons such as a butane-cut obtained from natural gas or from the stabilization of natural gasoline or a C₄ cut of cracking still gases or the like is introduced through line 10 into deisobutanizer tower 12. This feed material contains isobutane, normal

butane, and some propane and may also contain some olefins such as the butenes. Propane is unavoidably admixed with the other constituents because, in the preparation of the C₄ fraction, depropanization thereof is not or cannot be carried out to such an extent that a sharp separation is made between the C₃ and the C₄ hydrocarbons.

In the deisobutanizer tower 12, the isobutane in the C₄ hydrocarbon fraction is separated from the normal butane, which is removed as a bottoms stream through line 14. If any butenes are present, they will generally be found in varying amounts in both the overhead and the bottoms streams according to the particular fractionating conditions. The isobutane and the lower boiling hydrocarbons are taken off overhead through line 16 for condensation in condenser 18. The resulting condensate is collected in accumulator 20, from which a portion of the condensate is returned through line 21 to tower 12 as reflux.

The remainder of the isobutane condensate from accumulator 20 is passed through line 23 to the alkylation reactor or chamber 25, wherein alkylation of the isobutane with the butenes is effected in the presence of concentrated sulfuric acid. Butenes may be desirably introduced into reactor 25 through line 26 from a suitable outside source of supply. The molal ratio of the isobutane to the butenes introduced into reactor 25 should be at least 1:1 and preferably within the range of 2:1 to 10:1 in order to accomplish a substantial degree of alkylation. The excess isobutane may be obtained by recycling excess isobutane within the system or by introducing additional isobutane through line 28 from some extraneous source. The sulfuric acid, which acts as a catalyst for the alkylation reaction, should have a concentration of between 90 and 100% and preferably of about 95 to 98%. The acid may be supplied to reactor 25 as through lines 40 and 30.

In reactor 25 the isobutane and the butenes are brought into intimate contact with each other and with the sulfuric acid to effect the desired alkylation. The pressure within the reactor should be sufficient to maintain the isobutane and the butenes in liquid condition at the particular reaction temperature, which should be within the range of 0 to 100° F. and preferably within the range of 40 to 60° F. The ratio of acid to hydrocarbon is desirably maintained within the range of $\frac{1}{2}$ to 1 $\frac{1}{2}$ volumes of acid per volume of hydrocarbon feed to the reactor.

Reactor 25 is desirably provided with an agitating mechanism 32 to provide the necessary intimacy of mixing. Any suitable mixing device which provides a sufficient degree of agitation may be employed. The isobutane-butene mixture is maintained in reactor 25 for sufficient time to effect substantial alkylation of the isobutane with the butenes. Substantially complete consumption of the butenes can be effected under the proper alkylating conditions, which are well known to the art.

The acid-hydrocarbon mixture from reactor 25 is continuously withdrawn through line 34 into settling chamber 36, wherein the mixture separates into an upper hydrocarbon layer and a lower acid layer. This acid layer is withdrawn through line 37, and the greater portion thereof is preferably recycled through lines 38 and 30 to reactor 25 to effect alkylation of further isobu-

tane and butenes. A portion of the used sulfuric acid from settling chamber 36 may be continuously discharged from the system through line 39, and fresh make-up sulfuric acid may be continuously introduced into the system through line 40.

The upper hydrocarbon layer in settling chamber 36 is withdrawn through line 42 and is passed into neutralizer 44. In this chamber the hydrocarbon mixture is treated with a neutralizing agent, e. g., an alkaline solution such as a dilute aqueous caustic soda solution, which is introduced into this chamber through line 45. The neutralizing agent serves to neutralize the acidity of the hydrocarbons resulting from contact thereof with the acid in reactor 25. The alkaline solution separates out in the bottom of neutralizer 44 and is continuously withdrawn therefrom through line 46.

According to my invention, the neutralized hydrocarbon mixture is withdrawn from the top of neutralizer 44 through line 48 and is passed into a prefractionating tower 50. This hydrocarbon mixture comprises the alkylate formed in reactor 25, the excess isobutane, the normal butane introduced into the system along with the isobutane and the butenes, and any propane unavoidably admixed therewith. This hydrocarbon mixture is preferably preheated in a suitable heater 51 before introduction into prefractionator 50. Tower 50 is operated under such conditions that substantially all the propane and a substantial proportion of the isobutane are separated from the remainder of the hydrocarbon mixture. Preferably, the fractionating conditions are such that only a minimum amount or substantially none of the normal butane is separated from the hydrocarbon mixture along with the isobutane and the propane. The purpose of this prefractionation treatment is to concentrate the propane in a stream of relatively small volume at a point in the alkylation system where it can be most readily eliminated therefrom by fractionation.

The separated isobutane and propane are taken off overhead through line 52 for condensation in condenser 54. The resulting condensate is collected in accumulator 55, from which a sufficient portion of the condensate is returned through line 56 to tower 50 as reflux. The amount of reflux necessary to effect this prefractionation of propane and isobutane is surprisingly small, and a reflux ratio of about 1:1 to 1.5:1 (ratio of reflux to net overhead product) is usually sufficient.

Further in accordance with my invention, the remainder of the condensate from accumulator 55 is passed through line 58 to depropanizer 60, wherein the propane is separated from the isobutane admixed therewith. The separated isobutane is removed from tower 60 as a bottoms stream through line 61 and is desirably admixed with the C₄ hydrocarbon charge in line 23 passing to reactor 25. In this way a portion of the excess isobutane is recycled to reactor 25 to maintain the necessary excess of isobutane therein. The propane is removed as the overhead stream from tower 60 through line 62 for condensation in condenser 63, the condensate from which is collected in accumulator 64. This condensation is carried out to provide only sufficient reflux for tower 60, which reflux is supplied to tower 60 through line 65. The uncondensed propane is eliminated from the alkylation system through the valved vent line 66. If desired, a

portion of the propane-isobutane stream in line 58 may be passed directly to reactor 25 through line 61 according to the amount of propane that must be eliminated.

The bottoms stream from prefractionator 50 is passed through line 68 into debutanizer tower 70. This bottoms stream comprises the alkylate admixed with some isobutane and the normal butane. In debutanizer tower 70 the alkylate is separated from the isobutane and the normal butane, which are removed overhead through line 72 for condensation in condenser 73. The resulting condensate is collected in accumulator 74, from which a sufficient portion of the condensate is returned through line 75 to reflux tower 70. The remainder of the condensate is recycled through line 76 to deisobutanizer tower 12 for separation of the isobutane from the normal butane. The isobutane thus recovered supplies some of the excess isobutane required in reactor 25. If desired, line 77 may be provided for recycling of a portion or all of the isobutane in line 76 directly to the reactor when the percentage of normal butane in this isobutane stream is relatively small.

The alkylate is removed from the bottom of debutanizer tower 70 through line 78 into alkylate fractionator 80. If desired, the fractionating conditions in tower 70 may be maintained in such fashion that a portion of the butane is included in the alkylate bottoms stream to give the resulting motor fuel fraction any desired volatility. In tower 80 the alkylate is fractionated under conditions suitable for production of the desired high antiknock gasoline, which is removed overhead through line 81 for condensation in condenser 82. A portion of the condensate is returned through line 83 as reflux for tower 80. The remainder of the condensate is withdrawn from the system through line 84 and comprises the desired high antiknock aviation grade motor fuel. The higher boiling alkylate product is removed from the bottom of tower 80 through line 86 for disposal as desired.

In operation, it is generally desirable to maintain the proportion of propane in the reactor 25 below 3% by weight since the propane is inert as far as the alkylation reaction is concerned and since it also adversely affects the yield of alkylate if it is present in too great a proportion during alkylation. Accordingly, unless the propane is continuously vented or eliminated from the alkylation system in some fashion, it will be continuously recycled along with the isobutane and will gradually accumulate in the system and thereby adversely affect the alkylation reaction. It should be noted that the amount of propane vented through line 66 controls all of the fractionating operations prior to this point.

My invention provides a method of concentrating the propane in a stream of relatively small volume at a point in the alkylation system where it can be most readily eliminated. If the hydrocarbon effluent stream in line 48 is fractionated in one step solely for the purpose of removing the propane overhead, a relatively large tower will be necessary. Furthermore, a relatively high reflux ratio will be required in order to prevent a substantial amount of isobutane from being carried overhead with the propane and to prevent loss of isobutane. In addition, a substantial supply of heat will be necessary in order to provide the requisite stripping effect to strip the relatively small amount of propane from the relatively large amount of bottoms.

With my invention, these disadvantages can be avoided, and a superior separation can be obtained at the same time. The fractionation in prefractionator 50 is carried out such that a substantial proportion of the isobutane is carried off overhead with the propane and only sufficient reflux is required to prevent the removal of any normal butane in the overhead stream. In this manner, the propane is concentrated at a point in the alkylation system where it can be most readily eliminated therefrom in a stream having a total volume considerably less than the volume of the hydrocarbon effluent in line 48. Accordingly, the ease of separation of the propane from the isobutane in depropanizer tower 60 materially reduces the heating load and the other operating requirements necessary for the elimination of the propane from the system. The stripping of the propane from the isobutane in tower 60 is considerably less difficult because of the much smaller amount of material being handled in the elimination of the propane. Furthermore, the amount of isobutane lost with the eliminated propane is reduced to a substantially negligible minimum.

It will be appreciated that my invention is not necessarily limited to the use of concentrated sulfuric acid as the alkylation catalyst. Other suitable substances for effecting this reaction comprise aluminum chloride, phosphoric acid, hydrofluoric acid, and the like.

Although I have described a preferred form of embodiment of my invention, I am aware that modifications may be made thereto; therefore, only such limitations as appear in the claims appended hereinafter should be made.

I claim:

1. The process of alkylating an isoparaffin with a normally gaseous olefin to form high antiknock motor fuel, which comprises fractionating a feed stock containing the isoparaffin and unreactive hydrocarbons both higher boiling and lower boiling than the isoparaffin to separate the isoparaffin and the lower boiling hydrocarbons as overhead therefrom, contacting the isoparaffin overhead with the normally gaseous olefin in the presence of an alkylation catalyst to effect alkylation of the isoparaffin with the olefin, maintaining an excess of isoparaffin over that required to react with the olefin during alkylation, separating the resulting hydrocarbon mixture from the alkylation catalyst, subjecting the hydrocarbon mixture to a prefractionation to separate the lower boiling unreactive hydrocarbons and a portion only of the excess isoparaffin as overhead therefrom to concentrate the unreactive hydrocarbons in such overhead, passing such overhead to a zone independent of the zone of said prefractionation and there fractionating such overhead alone under fractionating conditions independent of fractionating conditions within the prefractionation zone to separate the unreactive lower boiling hydrocarbons from the excess isoparaffin therein, eliminating the separated unreactive hydrocarbons from the system, fractionating the remainder of said hydrocarbon mixture to separate the remaining isoparaffin from the alkylate, recycling the isoparaffin recovered in the system to the alkylation zone to maintain the excess of isoparaffin therein, and fractionating the alkylate to recover a high antiknock motor fuel.
2. The process of alkylating isobutane with a butene to form high antiknock motor fuel, which

comprises fractionating a C₄ fraction containing propane unavoidably admixed therewith to separate the isobutane and propane as overhead from the normal butane, contacting the isobutane overhead with a butene in the presence of concentrated sulfuric acid to effect alkylation of the isobutane with the butene, maintaining an excess of isobutane over that required to react with the butene during alkylation, separating the resulting hydrocarbon mixture from the sulfuric acid, heating the hydrocarbon mixture and subjecting it to a prefractionation to separate the propane and a portion only of the isobutane as overhead therefrom and to concentrate the propane in such overhead, supplying only sufficient reflux to the prefractionating zone to prevent separation of hydrocarbons higher boiling than the isobutane, passing such overhead to a zone independent of said prefractionation zone and there fractionating such overhead alone under fractionating conditions independent of fractionating conditions within the prefractionation zone to separate the propane from the isobutane, eliminating the propane from the system, fractionating the remainder of said hydrocarbon mixture to separate the remaining isobutane from the alkylate, recycling the separated isobutane to the alkylation zone to maintain the desired excess of isobutane therein, and fractionating the alkylate to recover a high antiknock motor fuel.

3. In the process of alkyllating isobutane with a normally gaseous olefin in the presence of concentrated sulfuric acid to form high antiknock motor fuel wherein the isobutane is admixed with propane and wherein the isobutane is present in excess of that required to react with the

olefin, the improvement which comprises heating the hydrocarbon effluent from the alkylation zone and subjecting it to a prefractionation to separate the propane and a portion only of the excess isobutane as overhead from the hydrocarbon effluent to concentrate the propane in an overhead stream, supplying only sufficient reflux to the prefractionating zone to prevent separation of hydrocarbons higher boiling than isobutane, passing such overhead stream to a zone independent of said prefractionation zone and there fractionating such overhead alone under fractionating conditions independent of fractionating conditions within the prefractionation zone to separate the propane from the isobutane admixed therewith, eliminating the propane from the system, recycling the separated isobutane to the alkylation zone, and fractionating the remaining hydrocarbon effluent to recover a high antiknock motor fuel, the reflux ratio in the prefractionating zone being maintained between about 1:1 and 1.5:1.
